Vest on upper left of page.

Primary Examiner—A. Hugo Word

Assistant Examiner—Celia A. Murphy

[57]

CLAIM

The ornamental design for weighted vest, as shown and
described.

DESCRIPTION

FIG. 1 is a front perspective view of weighted vest,
showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof; and

FIG. 7 is a bottom plan view thereof.

The broken lines shown throughout the views are un-
derstood to represent conventional stitching.
